(57) **CLAIM**

The ornamental design for a bottle with cap, as shown and described.

DESCRIPTION

FIG. 1 is a perspective view of a bottle with cap, showing the front and left side of our new design;

FIG. 2 is an elevational view of the front of the bottle with cap, the view of the back being substantially similar except for cap orientation;

FIG. 3 is an elevational view of a side of the bottle with cap;

FIG. 4 is an elevational view of the opposite side of the bottle with cap;

FIG. 5 is an plan view of the top of the bottle with cap; and,

FIG. 6 is a plan view of the bottom of the bottle with cap.
